UNITED STATES PATENT OFFICE.

MICHAEL G. PRIORE, OF YONKERS, NEW YORK.

DESIGN FOR A BRACKET.

SPECIFICATION forming part of Design No. 36,246, dated March 17, 1903.

Application filed January 27, 1903. Serial No. 140,812. Term of patent 3½ years.

To all whom it may concern:

Be it known that I, MICHAEL G. PRIORE, a citizen of the United States, residing in Yonkers, in the county of Westchester and State of New York, have invented and produced a certain new, original, and ornamental Design for a Bracket, of which the following is a specification, reference being had to the accompanying drawings, forming part thereof, in which—

Figure 1 is a face or front view of the bracket, and Fig. 2 is a side view.

The leading features of my design are the grotesque human face with open mouth surrounded by an incurving scroll and bearing a depending ornament of ribbons and leaves.

The ornamentation of the bracket is in high relief. The face occupies the central portion,

and above it is the scroll ornament, projecting beyond the face and having spreading incurving ends. At the upper overhanging portion of the scroll is a central foliate ornament, and on a raised central rib is a line of beads. Below the face is a garland of ribbons and leaves, forming the lower portion of the bracket.

I claim—

The ornamental design for a bracket, herein shown and described.

In testimony that I claim the invention above set forth I affix my signature in presence of two witnesses.

MICHAEL G. PRIORE.

Witnesses:

J. F. FLETCHER,
CHARLES R. SEARLE.
